Primary Examiner—Brian N. Vinson*Attorney, Agent, or Firm*—Reese Taylor[57] **CLAIM**

The ornamental design for a dispenser for soap or similar viscous material, as shown and described.

DESCRIPTION

FIG. 1 is a perspective view of a dispenser for soap or similar viscous material showing my new design;
FIG. 2 is a front elevational view thereof;
FIG. 3 is a rear elevational view thereof;
FIG. 4 is a side elevational view taken from the left of FIG. 1, the right side being a mirror image thereof;
FIG. 5 is a top plan view thereof; and,
FIG. 6 is a bottom plan view thereof.

FIG. 1

FIG. 2

FIG. 3

FIG. 4

FIG. 5

FIG. 6
